HAND MOUNTED REAR VIEW MIRROR

Albert Sargis, 300 Main St., P.O. Box 118,
New Britain, Conn. 06050

Filed July 9, 1974, Ser. No. 486,761

Term of patent 14 years

Int. Cl. D12—16

U.S. Cl. D12—189

FIG. 3

3

FIG. 2

FIG. 1

FIG. 4

FIG. 6

FIG. 5

FIG. 1 is a front elevational view of a hand mounted rear view mirror showing my new design;

FIG. 2 is a side elevational view thereof;

FIG. 3 is a top plan view thereof taken along the line 3—3 in FIG. 2;

FIG. 4 is a bottom plan view thereof taken along the line 4—4 in FIG. 2;

FIG. 5 is a front elevational view of a hand mounted rear view mirror showing a second embodiment of my new design; and

FIG. 6 is a bottom plan view of the embodiment shown in FIG. 5 taken along a line similar to 4—4 in FIG. 2.

I claim:

The ornamental design for a hand mounted rear view mirror, as shown.
